UNITED STATES PATENT OFFICE.

WILLIAM J. PATTERSON, OF PITTSBURG, PENNSYLVANIA, ASSIGNOR TO
HEYL & PATTERSON, INCORPORATED, OF PITTSBURG, PENNSYLVANIA,
A CORPORATION OF PENNSYLVANIA.

APPARATUS FOR MAKING UP TRAINS.

SPECIFICATION forming part of Letters Patent No. 783,130, dated February 21, 1905.

Application filed March 26, 1904. Serial No. 200,211.

To all whom it may concern:

Be it known that I, WILLIAM J. PATTERSON, a resident of Pittsburgh, in the county of Allegheny and State of Pennsylvania, have invented 5 a new and useful Improvement in Apparatus for Making Up Trains; and I do hereby declare the following to be a full, clear, and exact description thereof.

My invention relates to apparatus for making up trains of empty coal-cars.

In the mining of coal it is customary to load the coal in cars in the mine and run the cars out by an arrangement of tracks to the tipple where the coal is dumped. The empty cars 15 are then run off onto tracks and by car-hauls brought back to a point where the track slopes down, and the cars by their own gravity are brought into contact with each other and made up into trains. This method of making up 20 trains of empty cars is very injurious to the cars, for the reason that as the cars descend an incline their speed is accelerated and each succeeding car bumps into the preceding car with sufficient force to jar the cars violently, and 25 the result is a severe wear and tear upon the cars.

The object of my invention is to provide a device for making up trains of empty coal-cars whereby the cars move along gradually 30 on the track on which they are made up, so that each succeeding car does not move rapidly into contact with those that have preceded, so as to collide violently therewith.

To these ends my invention comprises, generally stated, in connection with a coal-handling plant, a return-track for the empty cars, said track having usually an upwardly-inclined portion and mechanism for carrying the cars up said inclined portion and a substantially horizontal platform at the upper 40 end of said inclined track where the car is disconnected from said hauling mechanism, whereby said car comes to a standstill and the next succeeding car pushes said car along the track where the train is to be made up.

To enable others skilled in the art to make and use my invention, I will describe the same

more fully, referring to the accompanying drawings, in which—

Figure 1 is a side elevation of my improved 50 train-making device. Fig. 2 is a plan view thereof.

Like numerals indicate like parts in each of the figures.

As my invention relates solely to the making up of the trains of empty cars, it has been deemed necessary only to illustrate this particular portion of the coal-handling device.

Accordingly the numeral 2 designates the return-track along which the empty cars are 60 brought from the tipple, said track being slightly inclined, so that the cars travel by gravity. The upwardly-inclined section 3 of the return-track is supported upon a suitable trestle-work 4, and in order to convey the 65 empty cars up this inclined portion 3 I employ a suitable car-haul. At the upper end of the trestle work 4, arranged within suitable bearings, is the shaft 5. Upon this shaft 5 is mounted the sprocket-wheel 6. This shaft 70 5 may be driven by any suitable power. At the lower end of the trestle 4 and journaled within suitable bearings is the shaft 7, and mounted on said shaft is the sprocket-wheel 8. An endless chain 9 engages the sprocket-wheels 6 and 8, said chain being provided at 75 intervals with the projections or dogs 10. These dogs 10 are adapted to engage the projections 11 on the cars 12. The chain 9 is supported from below by the channel-bar 13, 80 within which said chain travels and by which it is prevented from sagging.

At the lower end of the trestle 4 are the idle rollers 14, arranged at suitable intervals 85 apart, said rollers being journaled in the arms 15, said arms being mounted on the shafts 16 and the free ends of said arms carrying the weights 17. These weights 17 act to hold the rollers 14 normally up in position, (indicated in Fig. 1,) and upon these rollers the chain 9 90 travels. Adjacent to the upper end of the trestle 4 are the idle rollers 18, which support the chain at this point, and from this point on the chain 9 travels in substantially

a horizontal plane, as well as the upper section of the track 19. The upper end of the trestle 4 and the operative mechanism of the car-haul are inclosed in the house 20. The 5 track 19 extends out beyond the house 20 for a suitable distance according to the length of trains to be made up on said track, and while said track is substantially horizontal it may have a very slight downward grade, although 10 not sufficient to cause the cars to move at an accelerated speed when one car is moved by the other in manner hereinafter fully set forth.

When trains of coal-cars are to be made up, the empty cars as the coal is discharged therefrom are brought back by the track 2 to the foot of the inclined track 3, whereupon said cars are engaged by the projections 10 on the chain 9. As the said cars travel onto the track 3 over the track 2 with some impetus and it 15 is desired to have the projections 10 engage with the said cars gradually, so as to relieve the strain on the chain, the projections 11 on said cars will come in contact with the dogs 10 on the chain, and owing to the compressible 20 idle rollers 14 said chain will be pushed down and the car allowed to ride over the dog 10 until the speed of the car has been checked, so that the dogs 10 cannot engage the projections 11 on the cars too suddenly, so as to relieve 25 the strain on the chain. The weighted arms 15 bring said rollers 14 and the chain 9 back to normal position as soon as the dogs have taken hold of the cars. The cars are carried at a slow speed up the inclined track 35 3 by the chain 9, and said cars pass from the track 3 onto the horizontal track 18. The car is freed from the chain 9 just as the dogs 13 pass around the sprocket-wheels 6, and the car thereupon stops on the track 18 just beyond 40 the sprocket-wheel 6. The next succeeding car being carried up in the same manner pushes the preceding car along the track 18 a car's length; but as the movement of the succeeding car is even and gradual it does not 45 collide forcibly with the preceding car, but moves gradually into contact therewith and simply pushes the preceding car the distance of its length along the track 18. In like manner other succeeding cars are brought up and 50 push the preceding cars along the track 18 un-

til the train has been made up. In this manner sudden jarring and colliding of the cars of the trains is avoided and the lives of the cars increased.

It is apparent that while I have illustrated 55 and described my invention with reference to the making up of the trains of empty cars at the upper end of the car-haul the invention may be applied equally as well to making up the trains of empty cars at the foot of the car-haul. 60

What I claim as my invention is—

1. In a device for making up trains of empty coal-cars, the combination with the return-track, of mechanism for hauling the cars along 65 said track, means for automatically releasing the car from said hauling mechanism, and a substantially horizontal track connecting with said return-track at the point of release, whereby each car released will advance the preceding 70 car a car's length.

2. In a device for making up trains of empty coal-cars, the combination with the return-track, of an upwardly-inclined section, mechanism for hauling the cars up said inclined section, and a substantially horizontal section of track at the upper end of said inclined section, means for releasing the car from said hauling mechanism at said horizontal section, whereby each succeeding car, as it is released from the 80 hauling mechanism, pushes forward the preceding car in its path a car's length. 75

3. In a device for making up trains of empty coal-cars, the combination with the return-track of an upwardly-inclined section, an endless 85 chain arranged in connection with said inclined section and adapted to haul the cars up said section and a horizontal track-section at the upper end of said inclined track-section, the upper end of said chain being within said 90 horizontal track-section, and means for releasing the cars from said chain at said horizontal section, whereby each car released will advance the preceding car a car's length.

In testimony whereof I, the said WILLIAM 95 J. PATTERSON, have hereunto set my hand.

WILLIAM J. PATTERSON.
